UNITED STATES PATENT OFFICE

2,644,211

PIN FASTENER

Lawson D. Sumner, Lake George, Colo.

Application November 10, 1952, Serial No. 319,689

7 Claims. (Cl. 24—162)

1

My invention relates to an improved pin fastener for garments characterized by the ability to pin the garments effectively without at any time leaving exposed prongs which may injure users.

Pins are in essentially universal use as fasteners for garments because of their flexibility of application and convenience in use. However, even the safety pin is a dangerous instrument in the hands of babies and young children and it is common knowledge that many accidents occur in their use. The present invention provides a pin capable of all the uses of a conventional safety pin but is at the same time perfectly safe in use and, even if swallowed, cannot result in injury.

Briefly, the pin of the present invention uses a U-shaped frame with legs connected by a web. One leg has a pair of spaced holes which receive the prongs of a slidable carriage which open and close with respect to the other leg for pin action. The carriage is restrained in its outward, pin opening, movements and against excessive tilting by a linkage, and spring means is provided to urge the carriage to a prong closing position.

It is, therefore, a general object of the present invention to provide an improved pin characterized by safety in use and convenience in operation.

Another object of the present invention is to provide an improved pin in which the prongs are shielded at all times.

Still another object of the invention is to provide an improved pin wherein the prongs are held against separation from the remainder of the unit.

Yet another object of the present invention is to provide an improved pin wherein the prongs are biased to a closed position where their pointed ends are received in protecting recesses.

The novel features which I believe to be characteristic of my invention are set forth with particularity in the appended claims. My invention itself, however, both as to its organization and method of operation, together with further objects and advantages thereof, will best be understood by reference to the following description taken in connection with the accompanying drawing in which:

Figure 1 is a side-elevational view with parts in cross section showing a fastener built in accordance with the present invention and in fastening position on a garment;

Figure 2 is a fragmentary view of the fastener

2

of Figure 1 with the carriage and prongs retracted to opened position;

Figure 3 is a cross-sectional view through axis 3—3, Figure 2;

Figure 4 is a fragmentary view through axis 4—4, Figure 2; and

Figure 5 is a view in perspective of an alternative frame structure of the pin of the present invention.

Referring now to Figure 1, there is shown at 10 a U-shaped frame member having an upper leg 10a and a lower leg 10b substantially parallel to the upper leg. The legs are joined by a web 10c. As shown in Figure 3, the frame 10 is of circular cross-section. At its upper face 10d, Figure 3, the frame 10 receives the bracket indicated generally at 12. This bracket has a pair of upstanding parallel wings 12a and 12b. The web portion of the bracket between these wings conforms to the shape of the surface 10d and is soldered thereto, as indicated at 14, Figure 3. The upper leg 10a of the frame 10 and the bracket 12 are apertured at 10e, Figure 2, to define a pair of spaced openings through which the prongs 16a and 16b of the carriage 16 extend. This carriage has a U-shaped back member 16c to which the prongs 16a and 16b are fixed by soldering or other appropriate means.

The prongs 16a and 16b are of such length that when the carriage 16 is in the collapsed position of Figure 1, the prongs fully bridge the space between legs 10a and 10b. Thus pieces of cloth C positioned between the legs 10a and 10b are pierced by the prongs and are securely held together.

Briefly, the leg 10b has a pair of openings 10f in registry respectively with the openings 10e so that they can receive the prongs 16a and 16b as shown in Figure 1. The leg 10b is somewhat enlarged adjacent the openings 10f, as shown at 10g, to assure a firm contact between the upper margins of holes 10f and the cloth C, as shown in Figure 1.

Collapsing and retracting motions of the prongs are controlled by the crossed links 18 and 20, Figures 1, 2, and 3. As shown in Figure 1 and Figure 3, these links have outwardly extending trunnions 18a and 20a, respectively, which project through the holes 12c and 12d of the bracket 12, respectively. Thus, each link is supported for swinging motions about a point close to the corresponding opening 10e.

The link 18 extends from its trunnion 18a to the head portion 18b. Adjacent the head portion 18b the link passes through the carriage 16 at the

opening 16d, Figures 1 and 2. Similarly, the link 20 extends from the trunnion 20a to the bent over head 20b and adjacent the head passes through the opening 16e. At its intermediate portion the link 20 is offset at 20c, Figure 2, and in this offset region is apertured at 20d, as shown at Figure 3. The link 18, which is straight throughout its length, is loosely received in the aperture 20d so that the two links are interconnected for sliding movement with respect to each other.

The link 20 is urged to the collapsed position against the bracket 12 by the spring 22 which at end 22a seats against the bracket 12 and at the other end 22b rests against the link 20, all as shown in Figure 2. The link is shown in the fully collapsed position, Figure 1.

The links 18 and 20 anchor the carriage 16 for limited extending and retracting movements in relation to the frame 10 and against excessive tilting in respect to the frame. Outward or prong retracting motions of the carriage 16 are limited by the engagement of the headed ends 18b and 20b of the links against the outboard faces of the carriage 16, as shown in Figure 2. The parts are so proportioned that at this time the prongs 16a and 16b just extend into the openings 10e. The prong extending movement of the carriage 16 is limited by the engagement of the carriage 16 against the web portion of the bracket 12, as shown in Figure 1, the portions of bracket 12 against which the carriage seats being indicated at 12c.

Tilting motions of the carriage 16 are limited by the action of the links 18 and 20 which become cocked or otherwise arrest tilting motions of the carriage.

Figure 5 shows an alternative form of the frame 10. As shown, the frame is of channel-shaped configuration with the channel facing inwardly. The frame is defined by leg portions 110a and 110b and the web 110c. Holes 110e are provided in the leg portion 110a like the holes 10e. The lower leg 110b is provided with a pair of bridging tabs 110g which have openings 110f in registry with openings 110e, as shown in Figure 5. The frame of Figure 5 also has integral upstanding wing portions 112a and 112, respectively. These upstanding portions have openings 112d and 112e to receive the links 18 and 20.

The alternative structure of Figure 5 receives a carriage 16, spring 22, and links 18 and 20 in the same fashion as does the frame shown in Figures 1, 2, and 3. The links act to anchor the carriage against undue withdrawal and against tilting in the same respect as do the links shown in Figure 2.

The frame structure of Figure 5 has the advantage of being easily made from sheet metal by stamping and bending operations.

From the above description it will be evident that the pin cannot be closed beyond the position shown in Figure 1 on the one hand and cannot be opened beyond the position shown in Figure 2 on the other hand. In each of these extended positions, the prongs 16a and 16b are fully protected against accidental contact. Moreover, when the pin unit is fully released, the spring 22 forces the carriage to the closed or collapsed position of Figure 1 where the tips of the prongs rest in the openings 10f and are in a fully protected position. It will be apparent that while the pin effectively closes upon the cloth C, Figure 1, and thus achieves effective pin action, it does not under any circumstances assume a condition where the prongs 16a and 16b are exposed. It

can accordingly be used in the presence of babies and small children without fear of dangerous consequences.

While I have shown and described a specific embodiment of this invention, it will be obvious that various changes and modifications may be made without departing from the true spirit and scope of the invention. I, therefore, intend by the appended claims to cover all such modifications and changes as fall within the true spirit and scope of the invention.

What I claim as new and desire to secure by Letters Patent of the United States is:

1. A pin fastener for garments comprising in combination: a U-shaped frame having a pair of substantially parallel legs and a connecting web, one of the legs having a pair of spaced openings; a carriage having a pair of prongs received in said openings to open and close with respect to the other leg; said one leg having a pair of outwardly extending wings each having a pair of openings in substantial registry respectively with the openings in said one leg; a pair of crossed links having trunnions extending into the openings of the wings and slidably received in the carriage, respectively, one link having a slot to receive the other to define a sliding fit, and each link having a head portion adapted to seat on the carriage to limit the opening movements of the carriage.

2. A pin fastener for garments comprising in combination: a U-shaped frame of inwardly facing channel-shaped cross section, the frame having a pair of substantially parallel legs joined by a web, one of the legs having a pair of spaced openings and having outwardly extending wings, the other of the legs having a pair of channel-bridging tabs at its inner side, each having an opening in registry with one of the openings in the other leg; a carriage having a pair of prongs received in the openings of said one leg to open and close with respect to the other leg, the prongs being of sufficient length to extend into the openings in the tabs when the carriage is in the prong-extending condition; and means anchoring the carriage to the frame for opening and collapsing movements.

3. A pin fastener for garments comprising in combination: a U-shaped frame having a pair of substantially parallel legs and a connecting web, the legs each having a pair of openings, the openings of one leg being aligned with the openings in the other leg; a carriage having a pair of prongs received in the openings of one leg to open and close with respect to the other leg; crossed links pivoted respectively to the frame and slidably received in the carriage, respectively, one link having a slot to receive the other to define a sliding fit and each link having head portions adapted to seat on the carriage to limit the opening movement of the carriage; the prongs being of sufficient length to extend into the openings in the other leg when the carriage is in the collapsed condition.

4. A pin fastener for garments comprising in combination: a U-shaped frame having a pair of substantially parallel legs and a connecting web, one of the legs having a pair of spaced openings; a carriage having a pair of prongs received in said openings to open and close with respect to the other leg; crossed links pivoted respectively to the frame and slidably received in the carriage, respectively, one link having a slot to receive the other to define a sliding fit and each link having a head portion adapted to seat

5

on the carriage to limit the opening movements of the carriage; and a spring operable to urge one link in the collapsing direction to hold the carriage in prong-closing position.

5. A pin fastener for garments comprising in combination: a U-shaped frame having a pair of substantially parallel legs and a connecting web, one of the legs having a pair of spaced openings; a carriage having a pair of prongs received in said openings to open and close with respect to the other leg, the carriage having slots adjacent the prongs; and a pair of crossed links pivoted to the frame adjacent the openings respectively and received in the slots of the carriage, the links having head portions outboard the slots, and one link having a central opening through which the other link extends.

6. A pin fastener for garments comprising in combination: a U-shaped frame having a pair of substantially parallel legs and a connecting web, 20 one of the legs having a pair of spaced openings; a carriage having a pair of prongs received in

6

said openings to open and close with respect to the other leg; and crossed links pivoted to spaced points on the frame and slidably received at spaced points on the carriage, one link having a slot to receive the other to define a sliding fit and each link having a head portion adapted to seat on the carriage to limit the opening movements of the carriage.

7. A pin fastener for garments comprising in combination: a U-shaped frame having a pair of substantially parallel legs and a connecting web, one of the legs having a pair of spaced openings; a carriage having a pair of prongs received in said openings to open and close with respect to the other leg; and guide means anchored to the frame and to the carriage operable to arrest retracting movements of the carriage and to limit tilt of the same with respect to the frame.
